ROBERT W. BEARDSLEE, OF NEW YORK, N. Y., ASSIGNOR OF ONE-HALF TO THOMAS PORTER, OF BROOKLYN, NEW YORK.

SAFETY APPARATUS FOR ELEVATORS.

1,119,001.

Specification of Letters Patent.

Patented Dec. 1, 1914.

Application filed April 23, 1913. Serial No. 763,018.

To all whom it may concern:

Be it known that I, ROBERT W. BEARDSLEE, a citizen of the United States, residing at New York city, county of New York, 5 State of New York, have invented certain new and useful Improvements in Safety Apparatus for Elevators, of which the following is a clear, full, and exact description.

This invention relates to safety devices 10 for operating elevators and is particularly useful in connection with passenger elevators to prevent accidents when persons are passing on or off of the cars. In certain devices now in use for this purpose, the car 15 cannot be started while the gate is open. On account of the fact that the mechanisms connected with the controlling lever for starting and stopping the car get out of adjustment and are also subject to great 20 variations due to changes in temperature, it is found in practice that these devices do not operate with great accuracy. This is particularly true of hydraulic elevators in which the pilot valve is controlled by a cable 25 from the car lever and in which the locking takes place at the pilot valve. On account of changes in the length of the cable, it is difficult to maintain an unchanging relation between the position of the car lever and the 30 locking position of the pilot valve, for it is obvious that in order for such mechanism to operate, the mid-position of the lever must always correspond to the mid-position or locking position of the pilot valve. As a 35 result of this it frequently happens with such safety devices that the car may be operated and the gate opened in an unsafe manner, and in such a way as to endanger a passenger passing into or off the car.

40 One of the several objects of this invention is to provide a construction and arrangement for locking the car controlling lever which will permit a certain amount of "play" or "range" in the neutral position 45 or "stop" position, so that it is not necessary for the lever to be exactly in mid-position in order for the safety device to be operative.

A further object of the invention is to 50 provide an arrangement which will necessitate the car being stopped and standing substantially at the floor before the gate of that floor can be opened at all.

A further object of the invention is to 55 provide an improved contact device for the

purpose of closing one of the controlling circuits when the car is at the floor and which is adapted to operate without noise as the car passes the different floors without stopping.

60

The invention consists in the general combination of parts and simplicity of details hereinafter described, all of which contribute to produce an efficient safety device.

A preferred embodiment of my invention 65 will be particularly described in the following specification while the broad scope of my invention will be pointed out in the appended claims.

In the drawing which is diagrammatic, 70 Figure 1 is a general view showing a shaft with a car and with the safety devices; Fig. 2 is a detail upon an enlarged scale showing a circuit-closer controlled by the car lever and showing also the details of construction of the locking segment for the lever; and Fig. 3 is a diagrammatic view similar to Fig. 1 but illustrating the invention as applied to an electric elevator.

75

Referring more particularly to the parts, 80 1 and 2 represent the side walls of an elevator shaft 3 in which the car travels. At the floors which are indicated by the lines 5 and 6, gates 7 are provided which may be adapted to slide open in the usual manner on 85 guide rails 8. The car 4 is preferably controlled by a lever 9, the lower extremity whereof is formed with a cross-head 10 having sheaves 11 which maintain a constant connection with two runs 12, 13, of an operating cable in a well-known manner. The upper part of this lever 9 which projects above the segment 14 is provided with an electrically controlled lock 15 which preferably comprises an electro-magnet 16 having an armature 17 disposed above it, said armature being provided with a bolt 18 which is adapted to be drawn down when the magnet is energized in order to advance the bolt 18 into engagement with the segment. The armature 17 is normally held up so as to maintain the bolt 18 in a withdrawn position by a spring 19. The gates 7 are provided with electrically controlled locking devices or locks 20, and these locks are 90 connected in branch conductors 21 leading to contacts 22 which are most conveniently placed near the shaft wall 2, and the current for operating these locking devices 20 may be supplied by a source of E. M. F. 110

95

100

105

110

such as a battery 23 to which the branch conductors 21 are connected in parallel. The opposite side of the battery 23 is connected by a conductor 24 with a fixed contact 25 on the side of the car near the lever and preferably placed slightly to one side of the central or mid-position line 26 of the lever. Opposite to the contact 25 a similar contact 27 is similarly placed, and 10 this contact 27 is connected by a conductor 28 with a contact device 29 which is adapted to engage with the contacts 22 as the car arrives at each floor. When the car is stopping at a floor, the lever 9 operates to bridge 15 the contacts 25 and 27. In order to do this, I prefer to provide a circuit-closer 30 which is in the form of a trigger having a conducting finger 31 above its pivot pin 32, the lower part of the pivot being formed into 20 a yoke 33 which cooperates with a pin 34 fixed on the side of the lever. The path of travel of this pin 34 is indicated by the dotted line 35 in Fig. 2. When the lever is thrown to the right, the pin passes out of 25 engagement with the circuit-closer and throws the finger 31 over in engagement with the contact 25 and out of engagement with the contact 27. In a similar manner when the lever moves to the extreme left, the 30 contact is broken at this point. From this arrangement it will be seen that the circuit through each gate lock 20 is normally open at two points. When the car is just arriving 35 at a floor, the contact device 29 engages the contact 22 and closes the circuit at that point, and as the lever comes to its "stop" position or neutral position, it actuates the circuit-closer 30 to close the circuit between the contacts 25 and 27. The range of possible 40 positions of the car during which the circuit through the gate lock can be closed depends of course upon the length of each contact or shoe 22. If great accuracy is desired in this respect in the operation of 45 the elevator, the contact shoes 22 will be made very short and vice versa.

The electrically controlled locks 20 include bolts 36 which may be at the upper edges of the gates as indicated, and these 50 bolts 36 may have beveled faces 38 enabling the gates to be slammed shut. These bolts 36 pass up through solenoids 39 which form parts of these controlling locks so that when the current passes, the bolt will be drawn up 55 and release the gate.

I provide means for locking the lever 9 against movement as soon as the gate moves to open. In order to accomplish this I provide circuit-closing devices 40 including 60 contacts 41 and 42, the contact 42 of which is fixed while the contact 41 is carried by plunger 43 which is pressed toward the gate by a spring 44. The end of the plunger 43 is in contact with the edge of the gate so 65 that as the gate moves away, spring 44

brings the contacts 41 and 42 together. The current passes through the circuit closing device 40 by a conductor 45 from the battery 46 or other source of E. M. F. and returning by branch wire 47 connecting with the lead 48 from the solenoid, 16, the other terminal of the solenoid being connected by conductor 49 with the other side of the battery 46. 70

In order to enable the lever 9 to be locked to the segment 14 when the locking bolt 18 is advanced, I prefer to provide the middle point of the segment with a plurality of steps 50 forming shoulders 51 which the bolt 18 may engage. The segment preferably presents also a central notch 52 having an upwardly extending central projection or lug 53 and the bolt 18 is preferably formed with a notch 54 to engage this projection to lock the lever exactly in its middle position. The end of the bolt may drop into the space at each side of the lug 53, the bolt then being locked between the lug and the adjacent shoulder 51. In this way there are three locking positions of the lever 90 which are all neutral positions or "stop" positions for the lever. If the bolt should descend to the segment before the lever has come opposite the central notch 52, it will come upon the steps 50 which will lock the 95 lever against moving away from its neutral or stop position. Beyond the steps 50 the outer portions of the segment are provided with teeth which present shoulders 55 for the same general purpose as the shoulders 100 51. On account of these shoulders or teeth 55, if by accident the bolt 18 comes into engagement with the segment, for instance in case of breaking the spring 19, the lever could be moved only toward its "stop" or 105 neutral position thus preventing any movement of the lever in a direction to increase speed. The circuit-closer 30 gives a certain amount of flexibility of adjustment of the lever controlled contacts and is preferable to 110 having the lever close the contacts directly. For instance, if it is desired to slightly increase the arc of activity of the locking device on the segment, this can be accomplished by substituting a circuit-closer for 115 the circuit-closer 30, having a different shaped yoke and giving a wider range of actuating movement to the pin 34 without opening the circuit between the contacts 25 and 27. 120

Referring to the contact device 29, I prefer to construct the same in the form of a wheel or contact roller 56. The wheel 56 is preferably mounted on a lever 62 which is pulled by a spring 63 so that as the wheel 125 56 contacts each shoe 22, the shoe presses the wheel back slightly away from the wall. In other words, the contact shoes 22 are in the path of travel of the wheel. A stop 64 limits the outward movement of the 130

wheel, being engaged by the lever 62 for this purpose. The circuit closing finger 31 frictionally engages the contacts so that it holds itself in any position in which it is left by the pin 34.

My invention can also be readily applied to an electric elevator. One manner of applying the invention in such a case is illustrated in Fig. 3 in which 64 represents the 10 elevator shaft through which the car 65 passes, the said car being controlled by a lever 66 which, by its movement, affects the main operating circuit 67. The main circuit 67 includes a circuit-breaker or switch 68 which may be opened by energizing a solenoid 69. Any suitable wiring arrangement is adopted which will energize this solenoid when the car is at a floor and the lever 66 is in its "stop" or neutral position. This may 15 be done directly through the medium of the lever or indirectly through the door 70 which is arranged so that it cannot be opened unless the lever is in mid-position or stop position. As illustrated in Fig. 3, 20 I may form the door 70 of two sliding sections 71, 72 connected in operation through racks 73 and a pinion 74 so that the doors open in unison. The door 72 may have a projection 75 or other means for throwing 25 over a circuit closer 76 which closes a circuit through a conductor 77 passing to a locking device 78 on the lever and thence passing through the solenoid 69 before returning to the battery 79. The other door 30 35 40 45 50 55 60 65 70 75 80 85 90 95 100 105 110 115 120 125 130

move along the shaft to close a door which may have been left open accidentally and to facilitate repairing and adjustment of the elevator mechanism.

It is understood that the embodiment of 70 my invention described above is only one of the many forms my invention may take, and I therefore do not wish to be limited in the practice of the invention nor in the scope of the claims to the particular construction set forth. 75

What I claim as new is:—

1. In a safety device for elevators in combination, a car, a controlling lever carried thereby, a gate at a floor, an electrically-controlled lock for said gate, a circuit connected therewith adapted to unlock the gate when the circuit is closed, means controlled by the car's position for closing said circuit at one point, when the car is near a floor, 80 an electric contact carried on the car and arranged to positively close the said circuit at a second point by the act of swinging the said lever into its "stop" or neutral position when the car is near a floor, said circuit being normally closed at all other points 85 whereby the said gate may be opened from the exterior of the elevator shaft when the car has been left standing at a floor. 90

2. In a safety device for elevators, in combination, a car, a controlling lever carried thereby, a gate at a floor, an electrically controlled lock for said gate, a circuit connected therewith, normally open at only two points, means controlled by the car position 100 for closing said circuit at one of said points when the car is at the floor, means for closing said circuit by the swinging movement of said lever at the other of said normally open points when the lever is moving substantially into the neutral or "stop" position, a fixed member adjacent the lever having means operating to lock the lever in different "stop" positions and automatic means for locking the said lever in any one 110 of said "stop" positions while the said gate is open.

3. In a safety device for elevators in combination, a car, a controlling lever carried thereby, a gate at a floor, an electrically-controlled lock for said gate, a circuit connected therewith adapted to unlock the gate when the circuit is closed, means controlled by the car's position for closing said circuit at one point, when the car is near a floor, an 115 electric contact carried on the car and arranged to positively close the said circuit at a second point by the act of swinging the said lever into its "stop" or neutral position when the car is near a floor, said circuit being normally closed at all other points 120 whereby the said gate may be opened from the exterior of the elevator shaft when the car has been left standing at a floor, a locking 125 segment for locking said lever, a locking 130

In the operation of the device when the 50 car is at a floor, the contact device 85 strikes a fixed contact 86 corresponding to that floor. Then when the lever 66 is thrown to neutral position, the circuit is closed from the battery through the door lock 80 and through contacts 82 and 83 and through conductor 84 and contact device 85. When the door opens slightly, the door 72 closes a branch circuit through the circuit-closer 76 and contact 76^a through the conductor 77 and locking device 78 so as to lock the lever against the segment 87 and at the same time energizes the solenoid 69 and opens the operating circuit. Circuit through conductor 77 also passes through a button 77^a 65 which may be opened to enable the car to

bolt coöperating with said segment to lock said lever thereto in its "stop" position, and electrically-operated means arranged to actuate said lever locking bolt to lock the lever automatically when the gate is opened.

4. In a safety device for elevators in combination, a gate at a floor, an electrically controlled lock for said gate, a car, a lever on said car having a plurality of "stop" 10 positions, a circuit connected with said lock, and a circuit-closer which may close said circuit actuated by said lever only when in a "stop" position, an electrically actuated locking bolt on said lever, a segment co- 15 operating therewith to lock said lever in any of said "stop" positions, a second circuit for actuating said lever bolt, and means for closing said last named circuit automatically by the opening of said gate.

20 5. In an elevator safety device, in combination, a car, a lever for controlling the same, a gate having a gate lock, an electric circuit passing to said gate lock, means for closing the said circuit by said lever in a 25 plurality of "stop" positions to permit opening said gate, a circuit arranged to be closed by opening said gate, a segment for holding said lever thereto against movement in either direction in any of said stop positions, and means carried by the lever to lock 30 the same to said segment controlled by said last circuit.

35 6. In a safety device for elevators, in combination, a car, a controlling lever carried by said car, a segment having steps near the "stop" point thereof, an electrically controlled locking bolt carried by said lever and adapted to coöperate with said steps to lock 40 said lever to said segment in a plurality of different stop positions, a gate at the floor,

an electrically controlled gate locking device therefor, a circuit which may be closed by said lever in said stop positions and operating to actuate said gate locking device to permit the opening of said gate, and automatic means actuated when the gate is open to advance said bolt to engage with said segment.

45

7. In a safety device for elevators in combination, a gate at a floor, an electrically 50 controlled lock for said gate, a car, a lever on said car having a plurality of "stop" positions, a circuit connected with said lock, and a circuit-closer which may close said circuit closed by said lever when in a "stop" 55 position, contacts in said circuit arranged to be closed only when the car is at a floor, an electrically actuated locking bolt on said lever, a segment coöperating therewith to lock said lever in any of said "stop" positions, a second circuit for actuating said lever bolt, and means for closing said last named circuit automatically by the opening of said gate.

60

8. In a safety device for elevators in combination, a car, a controlling lever therefor having a plurality of "stop" positions for which the car will stop, electrically controlled locking means for locking said lever in any of said "stop" positions, a gate, and 70 means controlled by said gate for closing a circuit to said locking means when the gate is opened, to lock said lever.

65

Signed at New York this 21 day of April, 1912.
